SAFETY RAZOR

John A. Still, Bradford, Pa.

Application March 4, 1949, Serial No. 1,213

Term of patent 14 years

(Cl. D22—3)

To all whom it may concern:

Be it known that I, John A. Still, a citizen of the United States of America, residing at Bradford, county of McKean, and State of Pennsylvania, have invented a new, original, and ornamental Design for a Safety Razor, of which the following is a specification, reference being had to the accompanying drawing, forming a part thereof, wherein:

Figure 1 is a perspective view of a safety razor, showing my design;

Figure 2 is a view in front elevation of the safety razor;

Figure 3 is a top plan view of the safety razor;

Figure 4 is a top plan view of the safety razor;

Figure 5 is a bottom plan view of the safety razor; and

Figure 6 is a bottom plan view taken as shown from section 6—6 of Figure 3.

I claim:

The ornamental design for a safety razor, as shown.

JOHN A. STILL.
